UNITED STATES PATENT OFFICE

ALBERT L. CLAPP, OF DANVERS, MASSACHUSETTS

PROCESS OF UTILIZING SPENT LIME COOKING LIQUORS IN THE MANUFACTURE OF PAPER

No Drawing.

Application filed February 14, 1927. Serial No. 168,225

This invention relates to a process of recovering and utilizing in the manufacture of paper spent lime cooking liquors, such as are employed for cleansing and conditioning 5 cellulosic materials for beating and manufacture into paper, fiberboard or the like.

In manufacturing paper from cellulosic fibrous materials such as manila rope, bagging, burlap, rags, cotton waste and the like, 10 it is customary to subject such cellulosic material to the action of lime liquor at an elevated temperature and pressure in a digester. After digestion has been completed, the spent liquor is separated from the digested cellulosic material and is wasted. Such waste 15 liquor often constitutes a nuisance as it frequently must be filtered free from lime prior to discharge and the lime sludge disposed of independently, or where such requirements 20 need not be met it contaminates the water into which it is discharged and tends to destroy piscatorial life therein.

During digestion the lime liquor reacts with and dissolves from the cellulosic material such constituents as grease, oil, lignin and siliceous matter so that after digestion an appreciable portion of the lime has been spent by reaction with these constituents. As 25 a consequence it is often uneconomical and 30 inexpedient to reemploy such spent lime liquor for digesting other cellulosic material, as the spent products would become concentrated and contaminate rather than cleanse and condition cellulosic material digested 35 therein.

In accordance with the process of my invention I utilize such spent lime liquors together with the cellulosic material digested 40 therein for the manufacture of a waterproof, greaseproof and fireproof paper. As disclosed and claimed in my application Serial No. 94,329, filed March 12, 1926, such a paper may be produced by incorporating lime either alone or in admixture with asbestos into cellulosic fiber in the beater prior to running off 45 into paper on a paper machine. The paper filled with such material is then treated with sodium silicate solution. The solution reacts with the lime to produce a cementitious material which hardens or sets to a glass-like 50

compound which imparts water, grease and fire resistivity to the paper.

In producing such paper, in accordance with the present invention, I proceed as follows: The cellulosic material which is to be 55 employed as a raw material for making the paper, may be manila rope for example. Such rope is cut into relatively short lengths as by the use of a rag-cutter so-called, and then charged into a rotary digester. A liquor containing say from 5% to 20% lime based on the weight of dry fiber is then added to the digester and the charge is digested for the desired period of time and at the desired 60 temperature and pressure, depending on the characteristics of the raw material and the extent of conditioning which it is desired to effect. Thus, the charge may be digested from four to twenty-four hours at from fifteen to eighty pounds steam pressure,—a long 65 high-temperature digestion better conditioning the raw material than a short low-temperature digestion.

As a result of digestion, the fiber is cleansed and conditioned for beating as the lime acts 70 to dissolve the siliceous and ligneous content of the rope as well as foreign material such as oil, gum and grease and to soften and open up the fiber so that it responds more readily to hydration. In lieu of discharging 75 the digester contents onto a platform and allowing the liquor to drain into sewers or discharge basins as usual, in accordance with my process the digester contents are discharged directly into the beater engine as 80 the calcium constituent of the spent liquor is in a form which readily unites with sodium silicate solution to produce the cementitious material hereinbefore described. Moreover, the cellulosic material is not washed free 85 from lime in the beater engine as usually done by a revolving screen washer placed therein.

The beater charge is beaten out for the desired period of time, say from five to six hours, diluted to the proper consistency, run off on a 90 paper machine into paper, and the paper dried. The dry paper is treated with sodium silicate as by passing it through a solution of say about 20° Baumé to effect its complete penetration or treated to produce a penetration of 100

its surface portion only, as described in my application Serial No. 168,224, filed Feb. 14, 1927, and is then dried. Reaction takes place between the lime or calcium constituent and the sodium silicate to produce a cementitious material which upon drying sets to a glass-like compound which imparts water, grease, and fire resistivity to the paper. The sodium silicate apparently also reacts with the calcium compounds formed during digestion owing to its affinity for the calcium and sets free various filling and cementitious material in situ in the paper to produce an intimate bonding together of the fibers. The present process thus makes possible the production of papers and boards having the properties of greaseproofness, waterproofness and fireproofness by an economical method utilizing calcium constituent in a form which has heretofore been wasted. By my process, also, it is expedient to condition for beating cellulosic material such as waste paper, kraft, sulphite and other pulps by digestion in lime liquor, as the lime content of the spent liquor is incorporated into the paper.

Having thus described an embodiment of this invention it is obvious that changes and modifications might be made therein without departing from its spirit or scope as defined by the appended claims.

I do not herein claim broadly the treatment of paper filled with a material capable of reacting with sodium silicate solution to produce plastic setting compounds in situ in the paper, as this subject matter is disclosed and claimed in my application Serial No. 94,329, filed March 12, 1926.

I claim:

1. A process which comprises beating cellulosic fibrous material in the presence of spent lime cooking liquor, running the beaten material off on a paper machine, and treating the paper with sodium silicate solution.

2. A process which comprises adding spent lime cooking liquor to cellulosic fibrous material, beating the material in such spent liquor, running the beaten material off on a paper machine, and treating the paper with sodium silicate solution.

3. A process which comprises digesting cellulosic fibrous material in lime liquor, beating the digested material in the spent liquor of digestion, running the beaten material off on a paper machine, and treating the paper with sodium silicate solution.

4. A process which comprises digesting cellulosic fibrous material in lime liquor, beating the digested material in the spent liquor of digestion, running the beaten material off on a paper machine, drying the paper, and treating the dry paper with sodium silicate solution.

5. A process which comprises digesting cellulosic fibrous material in lime liquor, beating the digested material in the spent liquor

of digestion, running the beaten material off on a paper machine, treating the paper with sodium silicate solution, and drying the treated paper.

6. A process which comprises digesting cellulosic fibrous material at an elevated temperature and pressure in lime liquor, discharging the digested contents into a beater and beating in the presence of the spent liquor of digestion, running the beaten material off on a paper machine, treating the paper with a sodium silicate solution of about 20° Baumé, and drying the treated paper.

7. A process which comprises beating cellulosic fibrous material in the presence of spent lime cooking liquor, and running the beaten material associated with its cooking liquor off on a paper machine.

8. A paper filled with a substantial proportion of those calcium compounds which are produced by the digestion of cellulosic fibrous material in lime cooking liquor.

In testimony whereof I have affixed my signature.
